(57) **CLAIM**

The ornamental design for a table top, as shown and described.

DESCRIPTION

FIG. 1 is a perspective view of a table top in accordance with our new design, with portions of a table forming the environment of the table top and being illustrated in broken lines, which broken lines are for illustrative purposes only and form no part of the claimed design;

FIG. 2 is a front elevational view of the table top shown in FIG. 1, the rear, left-side, and right-side elevational views of the table top being the same as the front elevational view;

FIG. 3 is a top plan view thereof;

FIG. 4 is a bottom view thereof; and,

FIG. 5 is an enlarged elevation view of a corner portion of the table top shown in FIG. 2.
